UNITED STATES PATENT OFFICE.

KARL HERMAN, OF CHESTER, PENNSYLVANIA.

PUMP.

1,423,852.

Specification of Letters Patent. Patented July 25, 1922.

Application filed May 2, 1921. Serial No. 466,274.

To all whom it may concern:

Be it known that I, KARL HERMAN, a citizen of the United States, residing at Chester, in the county of Delaware, State of Pennsylvania, have invented certain new and useful Improvements in Pumps; and I do hereby declare the following to be a full, clear, and exact description of the invention, such as will enable others skilled in the art to 10 which it appertains to make and use the same.

This invention relates to pumps and more particularly to that class used for feeding steam boilers, in which event the pump is 15 steam operated or it may be driven with any desired fluid.

It is the object of the invention to provide a pump that will be very simple in construction and very efficient in its operation and in 20 which the motive fluid from the actuating rotor of the pump will join the discharge from the pump to contribute its heat thereto and will furthermore join the discharge in such manner as to augment the action of the 25 impelling member of the pump.

Other objects and advantages of the invention will be apparent from the following description.

In the drawings:

30 Figure 1 is a side elevation of a pump embodying the present invention.

Figure 2 is a vertical section on the staggered line 2—2 of Figure 3.

35 Figure 3 is a section on the staggered line 3—3 of Figure 2, the section including the axes of the rotors of the pump and of the rotatable check or check wheel of the pump.

Figure 4 is a section on the line 4—4 of 40 Figure 3, to include the driving rotor of the pump and the reversing valve.

Figure 5 is a section at right angles to Figure 4 in a plane including the axes of the inlet and discharge pipes of the driving rotor and showing the arrangement of the 45 reversing valve to establish communication between the inlet pipe and the inlet ports alternately.

Referring to the drawings, the present 50 pump comprises a casing 10 having a single inlet opening 11 at one end and having at its other end, in the construction illustrated, a pair of discharge openings 12, of which one may connect with a boiler feed pipe and the other with a pipe line for any purpose, it 55 being of course understood that any number of discharge outlets may be used.

Within the casing 10 is mounted a fluid

impelling rotor comprising a cylindrical body 13 having radiating longitudinal ribs 14 of the gear type and the upper and lower 60 walls of the casing are curved above and below this rotor as shown at 15 and 16 respectively and in close relation to which walls the ribs or teeth 14 move. The rotor 13 is fixed upon a shaft 17 that is journaled at 65 one end in a side of the casing 10 and at its other end in the outer wall of a chamber 18 that is formed on the plate 19 that is bolted against the opposite side of the casing 10, this chamber 18 being thus formed in what 70 may be termed a supplemental casing.

The chamber 18 is cylindrical and coaxial to the shaft 17 and within this chamber and 75 fixed upon the shaft 17, is disposed the driving rotor of the pump. The driving rotor comprises a cylindrical body 20 having a circumscribing flange 21 that radiates therefrom midway of its length and at opposite sides of this flange are the circumscribing series of ribs or wings 22 and 23 respectively. 80 One face of each rib is in a plane including the axis of the shaft 17 while the other face of each rib is at an acute angle to the first-named face. The acute angular faces of the ribs 22 are inclined oppositely to those of the ribs 23 and thus the radial faces of one set of ribs are presented in the opposite direction rotatably of the rotor to the corresponding faces of the other series of ribs. 85 Thus, if steam or other motive fluid be directed against the radial faces of one series of ribs and at right angles thereto, the driving rotor and therewith the impelling rotor will be driven in one direction and if the motive fluid be directed against the corresponding faces of the other set of ribs and in the same manner, the rotors will be 90 oppositely driven.

To admit a motive fluid, an inlet pipe 25 is 95 engaged with a valve casing 26 to which the pipe leads at one side and from the other side of which casing there lead the feed ducts or passages 27 and 28 that extend to the feed ports 29 and 30 that open through the wall of the chamber 18 in position to deliver motive fluid against the radial faces of the wings 22 and 23 respectively whereby to deliver motive fluid to either set of ribs. Within the valve chamber is a turning plug valve 31 having a passage 32 through it that 100 retains communication with the feed pipe 25 when shifted to register with the passages 27 and 28 interchangeably. The valve is 105 provided with a handle 33 for shifting it 110

and thus is provided a simple means for reversely actuating the driving rotor.

From the chamber 18 there leads an exhaust passage 34 in which is connected an exhaust pipe 35 that leads to the casing 10 at the discharge side of the impelling rotor, as and for the purpose to be presently explained.

It will be understood that with the rotor 13 actuated to move its lower side in Figure 2 in the direction of the discharge end of the casing water that may enter through the inlet opening 11 will be moved in the direction of the outlet end of the casing. To prevent the water from continuing around between the ribs 14 of the impelling rotor, a check wheel 36 is fixed upon a shaft 37 journaled in the sides of the casing 10 and in position to mesh its ribs or teeth 38 with those of the rotor 13, the teeth or ribs 38 moving in close relation to the upper wall of the casing 10 which is curved to conform to the curvature of the path of movement of the outer edges of the teeth or ribs 38.

Leading through the under side of the casing 10 is a duct or passage 39 that is forked to provide the branch passages 40 that lead through the bottom wall of the casing at points beneath check wheel 36 and in position to direct flow therefrom to the discharge openings 12 respectively. The discharge pipe 35 for the motive fluid is connected with an elbow 41 with which in turn is connected a pipe 42 leading to a L-connection 43 that is screwed into the passage 39 and thus the motive fluid after actuating the driving rotor, enters the casing 10 at the discharge side of the rotor 13 to join with the fluid impelled thereby and to contribute its heat thereto, the direction of movement of the motive fluid being such as to urge the impelled liquid to the discharge openings 12. The pipe 42 includes a T 44 with which is connected a drain cock 45 through the medium of which the apparatus may be drained, to prevent freezing when not in use.

It will of course be understood that the present pump may be employed in any capacity to which it is adapted and that in the place of steam, the driving rotor may be operated by compressed air or with other motive fluid. It will be further noted that when the pump is used in connection with a boiler or with any reservoir and it is desired to draw off the water this may be done by reversing the direction of operation of the impelling rotor 13, which is accomplished by shifting the valve 31 to correspondingly direct the motive fluid.

What is claimed is:

1. A pump comprising a casing, an im-

pelling rotor mounted in the casing, the casing having inlet and outlet openings, a driving rotor operatively connected with the impelling rotor, means for admitting a motive fluid to the driving rotor, means for discharging the motive fluid from the driving rotor to the impelled fluid within the casing, and means actuated by the impelling rotor for preventing retrogression of the impelled fluid.

2. A pump comprising a casing, an impelling rotor mounted in the casing, the casing having inlet and outlet openings, a driving rotor operatively connected with the impelling rotor, means for admitting a motive fluid to the driving rotor, means for discharging the motive fluid from the driving rotor to the impelled fluid within the casing and in the direction of the outlet, and means located between the impelling rotor and the outlet and actuated by said rotor for preventing retrogression of the impelled fluid.

3. A pump comprising a casing having inlet and outlet openings, an impelling rotor within the casing, a shaft upon which the rotor is fixed, a reversible driving rotor fixed upon the shaft and including two annular series of oppositely disposed ribs in radiating relation to the shaft, means for directing a motive fluid to the series of ribs interchangeably, means for conveying the motive fluid from the driving rotor and discharging it into the impelling rotor casing in the direction of the outlet of the casing, and a rotatable element driven by the impelling rotor and located between the rotor and the outlet of the casing for preventing the impelled fluid from being carried upwardly and backwardly by the impelling rotor.

4. A pump comprising a casing having inlet and outlet openings, an impelling rotor within the casing between said openings, a shaft upon which the rotor is fixed, a driving rotor fixed upon the shaft and including a pair of annular series of ribs having faces radiating from the shaft and disposed oppositely, means for delivering a motive fluid to the radial faces of the two series of ribs interchangeably, means for conveying motive fluid from the driving rotor into the casing between the rotor and the discharge opening of the casing, and a rotatable longitudinally ribbed check wheel meshing with and driven by the impelling rotor and located between the said rotor and the outlet of the casing for preventing the rotor from carrying the impelled fluid back toward the inlet.

In testimony whereof, I affix my signature.

KARL HERMAN
